UNITED STATES PATENT OFFICE

2,251,509

COLOR CLOCK

Verner E. Babcock, Port Clinton, Ohio

Application November 27, 1940, Serial No. 367,473

1 Claim. (Cl. 41—6)

This invention relates to a color clock, the general object of the invention being to provide means whereby a painter, artist or other person can readily ascertain what colors he should mix together and in what proportions to make certain colors which result from the combination of other colors of paints or the like.

Another object of the invention is to make the device in the form of a clock having dial means on both faces thereof so that one face of the clock can be used for securing various combinations of colors, such as for instance as those used by master painters and the dial means on the other face can be used by artists for mixing oil paints and the like.

Another object of the invention is to provide means for simultaneously adjusting the dial means on both faces from one operating member.

This invention also consists in certain other features of construction and in the combination and arrangement of the several parts to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:

Figure 1 is an elevational view with parts broken away showing one face of the device.

Figure 2 is a similar view but showing the opposite face thereof.

Figure 3 is a section on the line 3—3 of Figure 1.

Figure 4 is a section on the line 4—4 of Figure 1.

Figure 5 is an elevational view with the dial means removed from one face thereof and showing parts in section and parts broken away.

Figure 6 is a view of the stationary dial for the master painter.

Figure 7 is a view of the rotary dial for the master painter.

Figure 8 is a view of the rotary dial for the artist face of the device.

Figure 9 is a view in perspective of one of the supporting brackets.

Figure 10 is a fragmentary plan view of the inner frame and showing the knob for the operating shaft.

Figure 11 is a detail view showing the ring with a tongue thereon for holding certain parts of the device in position.

In these views the numeral 1 indicates a rim

5 of considerable width which has an annular flange 2 at one side thereof against which is pressed a transparent member 3 by a frame 4 which has an annular flange 5 at one side thereof which engages the transparent member. This frame is of circular shape and fits in the rim and it is formed with a central opening 5 for receiving parts of the device, the upper part 10 of the frame being formed by an arcuate block 6 the block being provided with prongs 7 which fit in recesses in adjacent parts of the frame as shown more clearly in Figure 10. A flanged ring 8 is removably held to the other side of the rim 1 by having tongues 9 struck therefrom to 15 engage notches 10 in the frame and this ring 8 holds a transparent member 11 in place, the adjacent side of the frame being provided with an annular flange 12 against which this transparent member 11 rests.

20 A centrally arranged stub shaft 13 is supported for rotary movement in the opening 5 by means of the brackets 14, one bracket being arranged on one side of the frame 4 and the other on the opposite side thereof. The brackets 25 are connected with the frame by screws 15 and one bracket having the right angular extending parts 16 thereon which engage notches in the other bracket. The ends of the shaft are reduced to form journals 17 which fit in holes 18 in the 30 brackets and also in holes in the stationary disks 19 and 19'. The extremities of the shaft 13 are of non-circular shape in cross section as shown at 20 to fit in non-circular holes in the rotating disks or dials 21 and 21' with the parts being 35 held on the shaft by the pins 22 passing through the non-circular parts thereof. A vertically arranged shaft 23 passes through the block 6 and a slot 24 in the top of the rim 1 and has a knob 25 at its upper end whereby the shaft 23 can be turned and this shaft 23 is connected with the shaft 13 by the beveled gears 26. Thus by turning the knob the shaft 23 is turned and this turning movement of the shaft 23 imparts turning movement to the shaft 13 through means of the gears 26 and this results in turning of the disks 21 and 21'.

Each disk is divided into inwardly tapering spaces by the lines 28 and each space has the words and colors thereon and each space is preferably of a color indicated by the word. Also, each disk is provided with the holes 29. The disk 21 for use by artists and the like contains colors which are used by an artist while the disk 21' has colors used by a master painter.

The stationary disk 19' which is covered by

the rotary disk 21' contains the characters 30 which will appear through the holes 29 in the disk 21' during the rotary movement of this disk 21' and these characters are to be used with a chart which will tell the colors indicated by the characters. For instance, if the indicia 1a on the stationary disk 19' of Figure 6 should appear through one of the openings 29 it would indicate that one part of the color represented by the character A on the chart is to be mixed with other colors appearing through the other holes 29. For instance, if the operator wishes to make up a quantity of paint of apricot color he moves the knob 25 until the disk 21' had the space thereon containing the word "apricot" and of apricot color reach the top of the device opposite the marker 32. Then the characters on the under disk would appear through the holes to show 1U, —R, that is 1 part of yellow ochre and a dash of Venetian red are to be added together and thinned with turpentine and added to the white lead to make apricot. On the other side of the device the characters 1B, 1P, —A and —C will appear through the holes and this will mean that 1 part burnt sienna, 1 part ultramarine blue, a dash of black and a dash of burnt umber are to be added together to make the amber color.

It will, of course, be understood that the code letters and the numerals indicating the amount of parts to be added can be changed as desired though, of course, this will necessitate changing the code.

Thus it will be seen that I have provided sim-

ple means for enabling one to mix the correct ingredients to secure desired colors.

It is thought from the foregoing description that the advantages and novel features of the invention will be readily apparent.

It is to be understood that changes may be made in the construction and in the combination and arrangement of the several parts provided that such changes fall within the scope of the appended claim.

Having described the invention, what is claimed as new is:

In a device of the class described, a circular frame, a rim enclosing the frame, a base for supporting the rim and frame, transparent members at both sides of the frame and spaced therefrom, stationary disks supported in the frame on both faces thereof, rotary disks covering the stationary disks and covered in turn by the transparent members, the stationary disks having indicating data on the front faces and the rotary disks having holes therein for exposing some of the data, the outer faces of the rotary disks having radiating spaces thereon marked to indicate various colors, a shaft supported for rotary movement in the frame and having its ends passing through the stationary disks and to which ends the rotary disks are connected for rotation with the shaft, a vertically arranged shaft supported in the frame and passing through the top of the rim, a knob connected with the upper end of the shaft and gearing connecting the two shafts together.

VERNER E. BABCOCK.
